UNITED STATES PATENT OFFICE.

EDWIN C. ROE, OF NEW BEDFORD, MASSACHUSETTS, AND LEONARD P. FRIEDER, OF NEW YORK, N. Y., ASSIGNEES TO NATIONAL SPUN SILK CO., INC., OF NEW BEDFORD, MASSACHUSETTS, A CORPORATION OF MASSACHUSETTS.

TEXTILE COILING MACHINE.

Original application filed August 1, 1924, Serial No. 729,452. Divided and this application filed October 3, 1925. Serial No. 60,163.

This invention relates to improvements in machines of the kind generally known in the textile trades as can coilers, for the reason that they are usually used to coil a web or similar collocation of textile fibers, usually called a sliver, in cans or other receptacles between successive operations in making yarns. As will be more clearly apparent later on, however, features of the invention are capable of use in machines for other specific purposes and, while the terms can coiler and sliver are repeatedly used herein, this is for convenience only, and the use of those terms is not to be considered as limiting the inventions either to such machines or to the handling of such materials.

One trouble experienced with all prior machines of the kind, so far as the applicants are aware, has been that changes in humidity or temperature, and the development of static conditions have interfered with the correct functioning of the machines. Such prior machines have also been unable to coil uniformly and satisfactorily, even under favorable conditions, light or fine slivers as well as they did the coarser ones. One of the objects of this invention is to provide a machine which is capable of handling a complete range of slivers, including the very fine ones, without interference or interruption because of the degree of fineness or because of unfavorable atmospheric or static conditions.

Another object of the invention is to provide stop motion devices controlled by the sliver for halting operations of the machine when certain conditions arise. While this mechanism may, for example, be so constructed as to be called into play by either the accumulation of the sliver in the cans or by a break or other interruption in the supply of sliver, the use of both is preferred in the present embodiment, thereby preventing the machine from packing the sliver in the cans so tightly that there is difficulty later in satisfactorily uncoiling it and at the same time providing a means for attracting the attention of the attendant if a machine has stopped because the can is filled or because of a break or lack of material to work upon.

While in the accompanying drawings the improvements are shown in the form they take when applied to or used in connection with a carding machine, it is obvious that the various parts may be modified and rearranged to cooperate with other machines or sources of supply of material.

With the foregoing and incidental objects in view, the invention consists in a novel construction and arrangement of parts, the novel features of which are pointed out in the claims and a preferred embodiment of which is shown in the drawings accompanying and forming a part of this specification.

Of the said drawings,

Fig. 1 is a left side view of the improved mechanism as it appears when applied to a carding machine;

Fig. 2 is a top plan view of the same mechanism as is shown in Fig. 1;

Fig. 3 is a section taken on the line 3—3 of Fig. 1;

Fig. 4 is a view partly in section, on the line 4—4 of Fig. 2;

Fig. 5 is a section through the base of the machine, on the line 5—5 of Fig. 3;

Fig. 6 is a detail of the sliver feeding rolls and the parts immediately associated therewith;

Fig. 7 is a detail of features of the stop motion mechanism for arresting operation of the machine when the sliver breaks or the supply of material is exhausted.

The embodiment shown in the drawings is, as before indicated, a satisfactory one for use in receiving and coiling a sliver of fibers as delivered from a carding machine. The mechanism is so arranged that the fibers are removed from the delivery roll of the carding machine and brought into what may, for convenience, be termed a loose strand which is, at the beginning of the operation of the machine, passed through suitable guides and into engagement with a pair of feeding rollers. These rollers are so mounted that they deliver the sliver to the interior of the can through an opening or passage which does not move relatively to the rolls and which is so short that there is substantially no resistance to the passage of the sliver through it. In prior devices

known to the applicants the feeding rollers are so mounted that a long guide is necessary to conduct the material from the rolls into the can and this guide has a movement relative to the feeding rolls. Such a long guide, coupled with its relative movement, makes it necessary for the rolls to push the sliver through the guide. It is obvious that this is unsatisfactory for handling fine slivers, for example, of silk, and that the movement of even fairly coarse material may easily be interfered with by the development of a static condition or by unfavorable degrees of temperature or humidity.

The preferred embodiment also comprises two stop motion connections. One of these is so arranged that when a can or corresponding receptacle is packed to its intended capacity the packed material acting against a movable head will lift a lug or other projection into a position where it will engage and actuate a stop motion element. The other stop motion connections comprise a member which is, in the preferred form, held in an ineffective position so long as material is coming through the mechanism. When there is a break or the supply of material is interrupted, the member referred to is automatically moved to a position where it will be effective to engage a stop motion element which may, as in the present construction, be the same one as is actuated when the can has been packed to its capacity.

Describing the construction in detail, and with reference to the accompanying drawings, the carding machine may have an extension such as indicated in dotted lines at 10, Fig. 1. The upper part of the coiling mechanism may be supported by a frame 111 secured to the extension 10 of the carding machine. The carding machine comprises a delivery roll 11, driven in a clockwise direction, Fig. 1, by any suitable belt or gear drive. Rigid with the delivery roll 11 is an internal gear 12, meshing with a pinion 13, Fig. 2. Rigid with the pinion 13 is a pinion 14 meshing with a pinion 15 which in turn meshes with a pinion or gear 16 secured to a short shaft 17 journaled in a boss or extension 18 of the frame 111. Secured to the short shaft 17 is a bevel gear 181 meshing with a corresponding bevel gear 19 attached to the vertical shaft 20. At its upper end the shaft 20 is provided with a gear 22 meshing with the teeth 24 of a ring gear forming a part of the movable head hereinafter described in more or less detail.

At its lower end the shaft 20 is provided with a pinion or gear 25, Figs. 3 and 5, meshing with the teeth of a large gear 26. Attached to the gear 26 is a smaller gear 27 meshing with a gear 28, which in turn meshes with teeth 29 on the rotary can base 31. The can base 31 is provided with

ribs corresponding with grooves in a stationary base 32 in such way that the rotary base can turn on its axis 33 and at the same time be suitably supported against any tendency to rock or tilt.

Both the gearing for driving the ring gear 24 and the head moving therewith, and the gearing for driving the rotary can base 31, are of the change-speed type, that is, gears having different gear ratios may readily be substituted, and corresponding relative adjustments made of the studs forming the bearings for the gears.

The rotary can base 31 has its upper surface suitably formed to receive the usual can or receptacle 35 in such way that rotation of the base will cause a corresponding rotation of the can.

The ring gear 24 is, as best shown in Fig. 4, loosely mounted in a circular bearing 36 in a plate 37 (see also Fig. 2) forming a part of the machine framing. Integral with the ring gear 24 are lugs 38 which form a convenient means by which a polished metal plate 39 may be secured to and caused to turn with the gear. This plate and its supporting connections form what is hereinafter referred to as the movable head for the can.

Rigid with the main frame 111 is a plate 41, slotted as at 42, Fig. 2, to serve as a guide for the web of fibers coming from the delivery roll 11. From the slot 42 the fibers pass through a guide 43, which is so constructed as further to collect the fibers into what has, for convenience, hereinbefore been termed a loose strand. The guide 43 is preferably on or forms a part of a pivoted trumpet 44. The sliver passes from the guide 43 downward through an eye at the upper end of the trumpet, and then downward through the eye of another guide or trumpet 46 to a pair of feeding rollers 47 and 48. The trumpet 46 is mounted for rotation about a vertical axis while the trumpet 44 is rotatable about a horizontal axis as shown at 51 in Fig. 1.

The feed rollers 47 and 48 are attached, respectively, to shafts 52 and 53, journaled at their ends in bearings supported by the ring gear 24 and which are preferably of the oilless type. Secured to the shaft 52 is a gear 54 protected by a housing 55 and extending through a suitable opening in the ring gear 24 into engagement with a stationary circular rack 56 secured to the plate 37. The construction is such that when the delivery roll 11 and the gearing previously described are put in motion the ring gear 24, and plate 39 attached thereto, will rotate counterclockwise (Fig. 2), and the gear 54 will cooperate with the stationary circular rack 56 to feed the sliver or strand of material down through an opening or a short guide such as 61, formed on or secured

to the plate 39. The short guide is, in some respects, preferable to simply an opening, as its top can be formed so as to conform somewhat to the configuration of the feeding rollers and thereby prevent the fibers from remaining in engagement with and being wound around the rolls.

From the foregoing it will be seen that the construction is such that the feeding rollers are mounted in close juxtaposition to the opening in the rotary head, and that, in fact, the material is practically delivered to the interior of the can without having to be pushed or forced through a chute or guide of substantial length. It will also be seen that there is no movement of the opening or guide 61 relative to the feeding rolls 47 and 48. The advantages of these features have already been pointed out in a general way.

The stop motion devices hereinbefore referred to may comprise any suitable electric or belt shifting mechanism, but in the present instance the showing is a more or less conventional one, of mechanism of the belt shifting type. A shaft, which may be movable endwise to operate a shifting fork, is shown at 57, Fig. 1. This shaft, as is usual in such constructions, may be latched in one position by a weighted bell crank 58 and moved to the other position by a counterbalance or spring, not shown, when the bell crank is lifted out of engagement with a collar 59 or other suitable projection on the shaft 57. This bell crank is connected by the usual wire or rod 61 to an arm 62 rigid with the trumpet 44. It is apparent that if the trumpet 44 is turned counterclockwise (Fig. 1) on its pivot 51, the bell crank 58 will be lifted to release the stop motion mechanism.

The trumpet 44 is lifted or rocked, as just mentioned, either when the can 35 has become packed to its capacity or when the sliver or strand of material has been broken or the supply of material exhausted. For the purpose of operating the stop motion mechanism when the first contingency arises, the rotary head, comprising the ring gear 24 and the polished metal plate 39, has one or more lugs such as shown at 63. When the can has been filled to its capacity the movable head will be lifted by the material, thereby raising the lug 63 until it will strike a suitably formed portion 64 on the trumpet 44 and rock the trumpet far enough to act through the connection 61 to free the stop motion mechanism.

In order to actuate the stop motion when the other contingency arises, that is, when the sliver breaks or the supply of material becomes exhausted, the ring gear 24 is provided with a shoulder or boss 65 (Figs. 2 and 7) to which is pivoted, at 66, a pawl 67. The pawl 67 is so mounted that it has a

tendency to move by gravity in one direction, and this tendency is increased by a portion 68 which serves as an additional weight at one side of the pivotal support for the pawl. The normal position of the pawl is shown in Fig. 7, in which position it will clear the shoulder or extension 64 on the trumpet 44. This is what is, at certain points herein, referred to as the ineffective position of the pawl.

In this ineffective position one edge of the pawl is in contact with a pin 71 projecting horizontally from the head 72 of a bolt 73, supported for longitudinal movement in the lug 65. Surrounding the bolt 73 is a light spring 74 which in the normal position of the parts, that is, while the sliver is running through the machine, is slightly compressed between the lug 65 and a pin 75 extending laterally from the bolt 73. The head 72 of the bolt is slotted, as indicated at 76 (Fig. 2), to cooperate with a pin 77 extending upward from the ring gear 24, thereby holding the bolt against rotation.

As before stated, the guide or trumpet 46 is rotatable about a vertical axis. Rigid with the guide is an arm 81 suitably slotted to engage a pin extending upward from the bolt 73. When the sliver is running through the machine it will hold the guide 46 in the position in which it is shown in Fig. 2, but if the sliver is broken or the supply of material forming it is exhausted, the guide will be freed and will then be swung to the position indicated by the dotted lines 82, by the spring 74 surrounding the bolt 73. This will cause the pin 71 (Fig. 7) to rock the pawl 67 on its pivot and bring the edge 83 thereof into or past a vertical position, in which position the upper tip of the pawl will be raised high enough to engage the shoulder 64 of the trumpet 44 and rock the trumpet in such a way as to actuate the stop motion connection 61 to arrest the movement of the mechanism.

In Fig. 2 the position of the can 35 is represented by dotted outlines, from which it will be seen that the axes of rotation of the can and of the ring gear 24 are not in alignment. In other words, one is off center with respect to the other. This causes the sliver to be coiled, as indicated more or less diagrammatically at 84, Fig. 3. This coiling continues until the can 35 is full, when the coil of material will come in contact with the underside of the polished metal plate 39. The plate will thereafter serve to pack the coiled material down in the can, doing this uniformly and without disarrangement of the sliver. The packing continues until the coiled material is packed closely enough to begin to lift the plate 39, and of course the ring gear 24 and the parts supported thereby. This will disengage the

gear 54 from the stationary circular rack 56 and will, as before described, bring the lug 63 up to a position where it will engage the shoulder 64 on the trumpet 44 and operate the stop motion connections.

This application is a division of application Serial No. 729,432, filed August 1, 1924, by the present applicants.

While the embodiment herein shown and described is admirably adapted to fulfill the objects primarily stated, it is not the desire to be limited to the particular embodiment, as the improvements are capable of various modifications and changes, all coming within the scope of the claims which follow.

What I claim is:

1. In a machine of the class described, the combination of a rotary can, a head for the can rotatable above and on a different axis than the axis of the can and having an opening through the head large enough for material to pass through said opening free from engagement with the edges of the opening, feeding devices operable in close juxtaposition with said opening, a pivoted guide for conducting the material to said

feeding devices, and means for driving the can, the head and the feeding devices.

2. In a machine of the class described, the combination of a rotary can, a ring gear 30 rotatable above and on a different axis than the axis of the can, a single plate attached to the under side of the ring gear to form a head for the can and containing an opening large enough for a roving to pass 35 through the opening without contacting the edges of the opening, a pair of feeding rolls rotatably supported in close juxtaposition to said opening by the ring gear, devices for directing the material from a source of supply to the feeding rolls comprising a guide pivotally supported by the ring gear, a shield attached to the aforesaid plate and constructed to prevent the material fed by the rolls from winding around said rolls, 45 and means for simultaneously rotating the can, the ring gear and the feeding rolls.

In testimony whereof we hereto affix our signatures.

EDWIN O. ROE.
LEONARD P. FRIEDER.
